L. J. MORAN

APPAREL HANGER

Filed May 31, 1922

L. J. Moran.

INVENTOR

BY J. O. Fowler.

ATTORNEY

UNITED STATES PATENT OFFICE.

LAWRENCE JOSEPH MORAN, OF BROOKLYN, NEW YORK.

APPAREL HANGER.

Application filed May 31, 1922. Serial No. 564,733.

To all whom it may concern:

Be it known that I, LAWRENCE JOSEPH MORAN, a citizen of the United States, and resident of Brooklyn, in the county of Kings and State of New York, have invented a certain new and useful Apparel Hanger, of which the following is a specification, the same being a full, clear, and exact description of the invention such as will enable others skilled in the art to which it appertains to make and use the same.

This invention relates to supports for articles of wear, etc., and particularly to devices constructed and arranged to hold hats, coats or other garments and articles in general, and the primary object of the invention is to provide a device of the class described upon which such articles may be serviceably supported and held against loss or displacement.

Another object of the invention contemplates the provision of a novel device of this nature which shall be of simple construction, inexpensive to manufacture and reliable, durable and efficient in practical use.

With the above named objects of the invention, and other objects and purposes hereinafter described, in view, the invention consists in the construction, arrangement, combination and operation of parts set forth hereinbelow.

In the drawings illustrative of embodiments of the invention, which accompany and form a part of this specification,

Figure 1 represents a front elevation of an article constructed according to my invention;

Figure 2 is a side view of the same; Figure 3 is a front elevation of another hanger in which the invention is embodied; and

Figure 4 is a side view thereof.

Referring more in detail to the drawings, the numeral 1 denotes the main frame or body portion of the hanger which may be made with supporting means as a screw hole 2 or hook 3, and which has at the lower part thereof an offset or substantially horizontal ledge 4 preferably formed with an orifice 5 and hinged at 12 so as to be foldable as regards the body of the hanger.

A preferably gravity retaining arm 6 is ordinarily mounted in a shiftable relation on the body 1 so as to work on the same as

by the employment of a slotted slide or body portion 7, which arm projects laterally away from the body and is then turned downwardly, the extreme lower portion of the arm terminating preferably in a locking or gripping finger 8 constructed and arranged to enter at will into the orifice 5. If desired, the arm 6 may be retained in adjusted position by friction between the parts 1 and 7.

Upon a suitable article, as a hat, being placed in operative contact with the hanger the ledge 4 will rest against the sweat band of the hat which is thus held from downward movement, and displacement of the same in an upward direction is prevented by the upper portion of the arm 6, the downwardly extending part of the latter serving to keep the hat brim from lateral movement, while the finger 8 of the said arm may rest upon the outside of the hat body and exert a positive grip on the same. The hanger thus forms a simple and efficient means for supporting hats in a detachable relation for general use, and is particularly adapted for service for that purpose in automobiles.

If preferred, the body of another embodiment of the hanger, as 1', may be formed with a slot 9 in which work prongs 10 and rivet 11 of the shiftable arm 6', and, if desired, the lower extremity of the said arm may terminate in two fingers 8' which may straddle the ledge 4' which latter may be adapted to be folded up toward the body 1' by the employment of a hinge 12. The supporting hook of the hanger may be linked to the body as illustrated at 3'. The operation of the elements of this embodiment of the invention is similar to that of the ones already described.

In cases where articles other than hats are to be supported by the hanger, the finger of the shiftable arm and the ledge may become positively engaged or interlocked, and in any event the said two parts co-operate to constitute a retaining means for the articles supported by the hanger.

I wish it to be understood that I do not desire to be limited to the particular use or the exact details of construction shown and described, for obvious modifications will occur to persons skilled in the art.

What I claim as my invention is:—

1. In a device of the class described, a frame having a body portion provided with

a hinged relatively horizontally disposed lower part to support an article, a shiftable arm having a body portion adapted to slide on the said frame body, the said arm projecting laterally from the frame and then extending in a downward direction, the extent of the downward movement of the arm being limited by the lower part of the frame, the lower extremity of the arm and 10 the said projecting part of the frame body having means to co-operate to constitute retaining means for an article supported by the device.

2. In a device of the class described, a frame having a lower portion adapted to engage the inner part of the body of a hat, and shiftable means mounted on the frame above the said lower portion and adapted at will to lie above and engage the hat brim 20 to prevent upward movement of the hat, the said lower portion being hinged to the frame and adapted when not in use to be folded between the frame and said shiftable means.

25 3. In a device of the class described, a body portion having a hinged projecting lower part to support an article, a shiftable arm to work on the body having a portion extending laterally from the same and then 30 extending in a downward direction, the lower extremity of the arm and the said projecting part of the body having means

to co-operate to constitute retaining means for an article supported by the device.

4. In a device of the class described, a body portion having a foldable projecting lower part to support an article, a shiftable arm to work on the body having a portion extending laterally from the same and then extending in a downward direction, the lower extremity of the arm and the said projecting part of the body having means to co-operate to constitute retaining means for an article supported by the device when in an operative position and the said lower part being adapted to be folded behind the shiftable arm when not in use.

5. In a device of the class described, a body portion having a hinged projecting lower part to support an article, a shiftable gravity arm to work on the body having a portion extending laterally from the same and then extending in a downward direction, the lower extremity of the arm and the said projecting part of the body having means to co-operate to constitute retaining means for an article supported by the device when in an operative position and the said lower part being adapted to be folded behind the shiftable arm when not in use.

Signed at Brooklyn, in the county of Kings and State of New York this 24th day of May A. D. 1922.

LAWRENCE JOSEPH MORAN.
